UNITED STATES PATENT OFFICE.

RALPH VOGEL, OF GERMANTOWN, PENNSYLVANIA.

CAR-BRAKE.

SPECIFICATION forming part of Letters Patent No. 784,906, dated March 14, 1905.

Application filed November 24, 1903. Serial No. 182,549.

To all whom it may concern:

Be it known that I, RALPH VOGEL, a citizen of the United States, residing at Germantown, county of Philadelphia, and State of Pennsylvania, have invented a certain new and useful Improvement in Car-Brakes, of which the following is a specification.

My invention relates to a new and useful improvement in car-brakes, and has for its object to provide a brake which can be quickly applied and will stop the car within a short distance, and thereby be of great advantage as an emergency-brake.

With these ends in view this invention consists in the details of construction and combination of elements hereinafter set forth, and then specifically designated by the claims.

In order that those skilled in the art to which this invention appertains may understand how to make and use the same, the construction and operation will now be described in detail, referring to the accompanying drawings, forming a part of this specification, in which—

Figure 1 is a side elevation of a portion of a car equipped with my improved brake; Fig. 2, a side elevation of a portion of a truck with my brake in operation; Fig. 3, a section on the line 3 3 of Fig. 1; Fig. 4, a section on the line 4 4 of Fig. 1.

A represents the car-body.

B represents the wheels of the two trucks located at each end of the car.

C represents sectional tracks arranged between the two trucks of the car and also forward and rearward of the trucks. These sectional tracks are normally suspended from the car and travel with the car a slight distance above the traction-rails; but when it is desired to stop the car within a short distance the sectional tracks forward of the trucks are lowered upon the rails, and as the end of the sectional tracks next to the wheels are beveled or inclined the wheels of the truck will run up upon the sectional track, and therefore the momentum of the car will be arrested very quickly. The rearward end of each sectional track is raised, as indicated at C', to prevent the wheels from running over that end of the track, and therefore after the car is resting

entirely upon the sectional tracks any further momentum of the car will be arrested on account of the friction between the tracks and the rails. Each of the tracks is composed of a number of sections, the sections being pivoted together, so that the tracks may bend horizontally. This is for the purpose of allowing the tracks to accommodate themselves to the curves in the road. The different sections of the tracks opposite one another are connected together by the braces D, said braces being pivoted at each end to the opposite sections of the tracks, so that the opposite sections will move together parallel with one another.

Any means may be employed for raising and lowering the tracks; but the means shown in the drawings consists of vertical bars E, which are adapted to slide in vertical standards F, depending from the car. The lower ends of the bars E are bent at right angles to form the pins G, which enter eyes H, extending laterally from the end sections of the track. The eyes H of each track are upon opposite sides, so that the forward eye will not strike the rearward bar when the car is passing upward upon the track. Any means may be employed for operating the bars E. That shown in the drawings consists of a system of sprocket-wheel and chains I, said chains extending to both platforms of the car, where they may be operated by a suitable crank J. These chains are adapted to operate ratchet-wheels K, which mesh with ratchet-teeth L, cut upon the bars E, and the chains are so connected that the tracks forward of the trucks will be operated from one platform and the other set of tracks will be operated from the other platform, so that the brakes may be applied no matter which way the car is traveling.

The operation of the device is as follows: By operating the proper crank J the tracks forward of the trucks will be lowered upon the main rails, and as the weight of these tracks will generate friction between themselves and the rail the pins G will pass forward out of the eyelets and then the wheels B of the truck will pass upward upon the tracks, and thus cause the car to come to a stop.

standstill. In order to return the parts to their normal position, the car is backed until the wheels leave the tracks and again rest upon the main rails and then the pins H will 5 enter the eyes upon the track and the track may be raised by revolving the crank J in the opposite direction.

M represents abutments, and normally the raised ends of the tracks lie against or in close 10 proximity to these abutments, so that in backing the car it is not necessary to stop the car at a precise moment, for the abutments will strike the tracks and push them along upon the rails, and therefore relieve the bars E of the 15 strain. If, for instance, the car is stopped upon a curve, the car is then backed until all the tracks are on straight rails, as otherwise the eyes H would not be in proper position to pass upon the pins G. The under surfaces 20 of the tracks C are so formed as to fit the rails and the upper surfaces of the tracks are identical with the upper surface of the main rails.

N represents posts extending downward 25 from the car and suitably braced in both directions.

O represents lugs extending inward from the sectional tracks, and these lugs are adapted to come in contact with the lower end of 30 the posts N when the sectional tracks are entirely underneath the wheels to prevent any liability of the wheels running over the upwardly-curved ends of said tracks.

P represents tubes extending downward 35 from the car, and when the sectional tracks are raised studs Q, carried by the tracks, are adapted to enter the lower end of said tubes, and thus prevent any liability of the tracks being accidentally displaced from the pins G 40 by the vibration of the car.

Of course I do not wish to be limited to the exact construction here shown, as slight modifications could be made without departing from the spirit of my invention.

45 Having thus fully described my invention, what I claim as new and useful is—

1. In combination with a car and car-wheels, sectional tracks arranged forward and rearward of the wheels, the ends of the sectional 50 tracks next to the wheels being beveled, and the other ends of the sectional tracks being raised, means for normally suspending said tracks from the car a slight distance above the rails, means for raising and lowering the

tracks, the means by which the tracks are automatically disengaged as the car moves forward, each track being composed of a number of sections pivoted together so that the tracks may bend horizontally, braces securing each side of opposite sections together, as and for 60 the purpose specified.

2. In a device of the character described, a car, car-wheels, main rail upon which the car-wheels run, sectional tracks arranged forward and rearward of the wheels, the end of each 65 track next to the wheels being beveled, the other ends of the tracks being raised, each track being composed of a number of sections pivoted together so as to bend horizontally, vertically-sliding bars, guideways depending 70 from the car in which said bars are adapted to slide, pins extending at right angles from the lower end of the bars, eyelets extending from the side of the tracks in which said pins are adapted to normally lie, thereby suspending 75 the tracks above the rail, means for raising and lowering said bars from the platform of the car, as and for the purpose specified.

3. In a device of the character described, a car, car-wheels, and main rail upon which the 80 car-wheels run, sectional tracks arranged forward and rearward of the wheels, the ends of the tracks next to the wheels being beveled, the other ends of the tracks being raised, each track being composed of a number of sections, 85 the sections being pivoted together so that the track may be bent horizontally, eyes extending laterally from the end sections of the tracks, one eye upon one side and the other upon the other side, vertically-sliding bars, 90 guideways depending from the car in which said bars are adapted to slide, pins extending at right angles from the lower end of the bars and adapted to normally lie within the eyelets to suspend the tracks above the rails, abutments carried by the car against which the raised ends of the tracks are adapted to normally rest, means for raising and lowering the 95 bars, cross-braces securing together the opposite sections of the tracks, as and for the 100 purpose specified.

In testimony whereof I have hereunto affixed my signature in the presence of two subscribing witnesses.

RALPH VOGEL.
